ORNAMENTAL MATERIAL

James T. Dowdall, Gloversville, N. Y., assignor to
 Gloversville Welt Co. Inc., Gloversville, N. Y.,
 a corporation of New York

Application December 19, 1934, Serial No. 758,216

3 Claims. (Cl. 2—278)

My invention relates to a new and improved ornamental material.

One of the objects of my invention is to provide an ornamental glove.

5 Another object of my invention is to provide an ornamental glove having a slitted body, and with pieces of applied material suitably associated with the slit or slits in said body.

10 Another object of my invention is to provide a simple and convenient method for making said ornamental material.

Other objects of my invention will be set forth in the following description and drawing which illustrates a preferred embodiment thereof, it

15 being understood that the above statements of the objects of my invention is intended to generally explain the same without limiting it in any manner.

Fig. 1 is a rear plan view of a glove to which 20 the invention is applied.

Fig. 2 is a plan view showing the slitted blank to which the additional material is applied.

Fig. 3 is a diagrammatic view showing a detail 25 of the sewing mechanism which is utilized in order to make the ornamental material.

Fig. 4 is a sectional view on the line 4—4 of Fig. 3.

Fig. 5 is a plan view of the outer surface of the ornamental material.

30 Fig. 6 is a plan view of the inner surface of the ornamental material.

Fig. 7 is a sectional view on the line 7—7 of Fig. 6.

Referring to Fig. 1 the glove 1 may be made 35 of any suitable material, such as leather or the like. The back of the palm portion of the glove is provided with one or more slits, in which the applied material is caused to appear.

In this particular embodiment, and referring 40 particularly to Fig. 2, three such slits 2 are provided in the material of the glove.

While I have shown the invention applied to a glove, the same could be applied to any suitable object, such as shoes, handbags and various 45 other objects. It has been well-known for many years to make gloves, shoes, and hand-bags, from leather or from woven fabrics.

Referring to Fig. 7, this shows a tape T whose color preferably contrasts with the color of the 50 material 1. For example, if the glove has a white color, the tape can have a brown color. This tape is made of leather or any suitable fabric, and it is freely bendable.

The transverse section of the tape is dome- 55 shaped in the completed ornamental material,

and a cord 3 is provided in order to secure this dome-shaped cross section in the flexible tape, which may be resilient or stretchable, or non-stretchable.

The cord 3 may have the same color as the 5 tape T.

As shown in Fig. 7, the cord 3 is pushed partially through one of the slits 2 and an exposed part of the tape T is thereby bulged and exposed above the outer or fair surface 4 of the glove 10 material. This produces an imitation piping which is securely kept in position and which can be made at minimum cost.

The tape T is stitched to the material of the glove 1. For this purpose I prefer to use a two- 15 needle sewing machine, in which each of the needles is reciprocated along a line transverse to the line of stitch.

Referring to Fig. 4, this shows a work-supporting plate 5 over which the pieces of material to 20 be stitched, are fed. Said plate 5 is provided with a pair of longitudinal slots or openings 6. A pair of feed dogs 7 and 7a are provided.

As shown in the plan view of Fig. 3, each of 25 said feed dogs 7 and 7a has an L-shape in horizontal plan view, and said feed dogs 7 and 7a are respectively provided with teeth 8 and 8a. Each of said feed dogs is given the familiar four-motion movement.

The needles N and Na reciprocate vertically 30 through the opening 9 which is provided in the workplate 5. Each of the needles N and Na makes a stitch which is close to the central longitudinal line of the opening 9, and it also makes a stitch which is spaced a greater distance from said 35 central line. When one of the needles makes a stitch which is close to said central line, the other needle simultaneously forms a stitch which is relatively remote from said central line. That is, the needles N and Na are vertically reciprocated 40 in unison and they are also laterally reciprocated in unison.

Referring to Fig. 6 the needle Na forms the 45 needle loops 10 and 10a. The needle N forms the needle loops 11 and 11a.

A bobbin is utilized which has a bobbin thread 12.

Starting from the bottom of Fig. 6, the needles first form the bottom pair of loops 10 and 11a. 50 The needles then form the second pair of needle loops 10a and 11. After the first pair of loops 10 and 11a have been formed, the bobbin thread 12 is passed through the same under suitable tension, so that said threads are pulled tightly 55

until they lie substantially parallel to the underside of the glove material.

The bobbin thread is first passed through a needle loop 10 and then through the companion 5 needle loop 11a.

Referring to the second pair of needle loops 10a and 11, the bobbin thread is then passed through the loop 10a and then through the needle loop 11. This method of sewing is continued.

10 The longitudinal legs or edge-portions of the tape extend laterally and outwardly from the central dome-shaped part thereof, so as to form tape edge-portions 14 and 14a.

None of the stitches pass through the cord 3. 15 All of the stitches may pass through the tape T or if desired, the outer stitches 10 and 11 may pass through the material of the glove 1, without passing through the tape T.

The inner stitches represented by the loops 10a 20 and 11a preferably pass through the dome-shaped part of the tape and such stitches may pass between the edges of the slits 2 so that they do not engage the material of the glove. Said stitches may engage said glove material.

25 Referring to Fig. 7, the point A represents the line along which the inner stitches 11a pass through the tape, and the point B represents the line through which the outer stitches 11 pass through the material of the glove.

30 Fig. 5 shows the outer or fair side of the material. This shows the zigzag thread elements 15 which are located between the points at which the loops penetrate to the inner side of the fabric.

35 It is to be understood that Fig. 7 is diagrammatic and the edges of the tape are shown as being slightly spaced from the underside of the glove material, in order to illustrate the formation more clearly.

40 In actual practice the tension on the needle loops draws the longitudinal legs of the tape tightly against the inner or concealed side of the glove material.

Prior to sewing the glove material and the tape 45 and the cord together, the tape and the cord can be inserted into the position generally shown in Fig. 7. The tape then has a friction fit between the edges of the slit 2 so that the parts which are thus assembled can be fed to the sewing 50 machine.

In making a glove the pieces of tape T and the cords 3 are sewed to the blank or trunk of the glove while said blank is in the flat or open condition, and the sewing of the glove-blank is 55 then completed in the usual manner.

I have shown a preferred embodiment of my invention but it is clear that numerous changes and omissions can be made without departing from its spirit.

60 In particular the claims for the article of manufacture are not to be restricted to the particular methods specified herein.

For convenience the glove material may be 65 designated as the base material and since the slits 2 are of restricted length they may be specified as slits having closed ends.

Referring to Fig. 7, it will be noted that the tape

is located between the cord and the longitudinal walls of the respective slit. Likewise, in the preferred embodiment the tape completely encloses the cord so that the cord cannot drop out of position even though the stitches skip the cord. 5

I have shown the use of stitches to connect the parts of the ornamental fabric, but adhesive or other means could be utilized, if desired.

While I have shown a cord, and in particular, a cord having a cylindrical cross section, it is to 10 be understood that this type of cord could be replaced by any suitable stuffing member or stuffing means having any desired cross section or shape, and that any suitable type of stuffing member is included by the term "cord" whenever 15 said term is used either in the description or claims.

I claim:

1. An ornamental material comprising a base material having separated edges, a tape located 20 at the inner side of said base material and having a portion thereof located and exposed between said separated edges, said portion of the tape having a transverse curved cross section, a cord substantially located within said exposed portion 25 of the tape, said tape having its inner portions transversely and outwardly located with respect to said separated edges, stitches located on each side of said tape, said stitches having loops which pass through said slit and which pass through the tape and which skip said cord, said stitches having additional loops which pass through said base material along lines which are outwardly and laterally spaced from said separated edges, and which skip said tape and said cord, said 30 stitches being connected by zigzag thread elements, at the fair side of the base sheet. 35

2. An ornamental material comprising a base material having separated edges, a tape having a portion thereof of curved transverse cross section and located between said separated edges, a cord located between said separated edges, the tape being between said cord separated edges, and stitches connecting said tape to said base material, some of said stitches passing between said 40 separated edges and said tape and skipping the cord, the other stitches passing only through the base material. 45

3. Ornamental material comprising base material having separated edges, an ornamental tape having a portion thereof located and exposed between said separated edges, the longitudinal edge portions of said tape being bent laterally away from said exposed portion and underlying the rear face of said base material, a cord located 50 within the exposed portion of the tape, and stitches having thread elements which pass through said base material and which connect said tape to said base material, said stitches having zig-zag thread elements on each side of the 55 exposed portion of the tape at the fair side of the fabric, and having connected loops at the rear side of the fabric, said longitudinal end portions of the tape being located between the rear face of the base material and said loops. 60

JAMES T. DOWDALL.
